C. P. Goepel

UNITED STATES PATENT OFFICE.

LOUISE R. ALLEN, OF NEW YORK, N. Y.

DESIGN FOR A CHAIN PULL FOR ELECTRICAL-LAMP SOCKETS.

59,054.

Specification for Design.

Patented Sept. 20, 1921.

Application filed February 18, 1921. Serial No. 446,193. Term of patent 3½ years.

To all whom it may concern:

Be it known that I, LOUISE R. ALLEN, a citizen of the United States, and resident of the borough of Manhattan, city, county, and State of New York, have invented a certain new, original, and ornamental Design for Chain Pulls, of which the following is a specification.

My new design is illustrated in the accompanying drawing, in which the figure is a contracted side elevation of my design.

I claim:

The ornamental design for a chain pull for electrical lamp sockets, as shown.

LOUISE R. ALLEN.
